US00D531140S

(12) **United States Design Patent** (10) Patent No.: **US D531,140 S**
(45) Date of Patent: **** Oct. 31, 2006**

(54) **LIGHT EMITTING SEMICONDUCTOR DEVICE**

(75) Inventors: **Kuniaki Konno**, Yokohama (JP);
Hiroaki Oshio, Kitakyushu (JP)

(73) Assignee: **Kabushiki Kaisha Toshiba** (JP)

(**) Term: **14 Years**

(21) Appl. No.: **29/242,542**

(22) Filed: **Nov. 14, 2005**

(51) LOC (8) Cl. **13-03**

(52) U.S. Cl. **D13/180**; D13/182

(58) Field of Classification Search **D13/180**,

**D13/182; D26/2; 257/79, 80, 81, 82, 88,
257/89, 95, 98, 99, 100, 678, 680, 433, 434,
257/666; 313/483, 498, 500; 361/820; 362/235,
362/249, 555, 800; 372/45.01**

See application file for complete search history.

(57) **CLAIM**

The ornamental design for a light emitting semiconductor device, as shown and described.

DESCRIPTION

FIG. 1 is a front, bottom and right side perspective view of a light emitting semiconductor device, showing our new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof; and,

FIG. 7 is a bottom plan view thereof.
